United States Patent Office

Des. 182,578
Patented Apr. 22, 1958

182,578

CLIPBOARD

Jack Fairchild Fleming, Summit, N. J., assignor to Sterling
Plastics Co., Union, N. J., a corporation of New Jersey

Application June 13, 1957, Serial No. 46,577

Term of patent 14 years

(Cl. D74—1)

FIG. 1

FIG. 4

Fig. 1 is a top plan view of a clip board embodying my new design;

Fig. 2 is a side elevation thereof;

Fig. 3 is a bottom plan view thereof; and

Fig. 4 is a rear view thereof.

I claim:

The ornamental design for a clipboard, substantially as shown.
